SANTA CLAUS CLOTHES PIN

Perry Feuer, Roslyn, N.Y., assignor to Creative Creations, Inc., New York, N.Y.

Filed Nov. 25, 1970, Ser. No. 26,164

Term of patent 14 years

Int. Cl. D7—05

U.S. Cl. D49—1

FIG. 1 is a front view of the design showing the clothes pin and the decorative Santa Claus configuration mounted on the front of the clothes pin;

FIG. 2 is a right side view of the design;

FIG. 3 is a rear view of the design;

FIG. 4 is a left side view of the design;

FIG. 5 is a top view of the design; and

FIG. 6 is a bottom view of the design.

I claim:

The ornamental design for a Santa Claus clothes pin, as shown.
